DESIGN FOR A SUCTION NOZZLE

Waldo E. Foster, Minneapolis, Minn., assignor to
Conveyors Incorporated, St. Paul, Minn., a corporation of Minnesota

Application January 29, 1945, Serial No. 117,646

Term of patent 14 years

(Cl. D9—5)

To all whom it may concern:

Be it known that I, Waldo E. Foster, a citizen of the United States, residing at Minneapolis, in the county of Hennepin and State of Minnesota, have invented a new, original, and ornamental Design for a Suction Nozzle, of which the following is a specification, reference being had to the accompanying drawing, forming part thereof.

Figure 1 is a front elevational view of a suction nozzle with the aperture covering plate removed showing my new design;

Figure 2 is a view similar to Figure 1 showing the suction nozzle aperture covering plate in position;

Figure 3 is a bottom plan view of the suction nozzle shown in Figure 1;

Figure 4 is a side elevational view of the suction nozzle as shown in Figure 2; and

Figure 5 is a perspective view of the same.

I claim:

The ornamental design for a suction nozzle, as shown.

WALDO E. FOSTER.
